(57) **CLAIM**

The ornamental design for a hemispherical shaped light emitting digital display, as shown and described.

DESCRIPTION

FIG. 1 is a perspective view of a hemispherical shaped light emitting digital display showing the design, oblique lines on outward facing surfaces indicating light emitting faces;
FIG. 2 is a front elevation view thereof;
FIG. 3 is a right elevation view thereof;
FIG. 4 is a left elevation view thereof;
FIG. 5 is a back elevation view thereof; and,
FIG. 6 is a top plan view thereof.

The broken lines of FIG. 1 showing the outline of a person are unclaimed portions of the environment and form no part of the claimed design. The remaining broken lines of FIG. 1 through FIG. 6 indicate unclaimed portions of the design.
